SPRING GROUP ASSEMBLY

John E. Flesch, Los Angeles, Calif., assignor to
American Steel Foundries, Chicago, Ill., a corporation of New Jersey

Application April 21, 1950, Serial No. 157,388

19 Claims. (Cl. 267—9)

1

This invention relates to package spring groups and more particularly to a novel arrangement for locking such a package in assembled relationship.

A general object of the invention is to provide a novel locking arrangement which may be easily applied and removed from the package and which will not interfere with the operation thereof.

A further object of the invention is to provide a novel locking device which may be readily incorporated in a spring group and which may be easily dismantled to accommodate disassembly of the spring group.

Another object of the invention is to devise a compact, simple locking arrangement which may be easily and inexpensively manufactured and which will positively limit expansion of the package whereby the parts are prevented from accidentally disassembling and causing injury or damage.

A different object of the invention is to provide a locking arrangement which will remain in the package at all times and is removable to permit dismantling.

A more specific object of the invention is to provide a removable, rugged lock assembly which will fit into the limited space in a friction shoe carrier on one plate and interlock with a friction casing on the other plate.

These and other objects of the invention will become more apparent from the specification and the drawings, wherein:

Figure 1 is a top plan view, partly in section, of a package spring group incorporating the invention, the section being taken substantially on the line 1—1 of Figure 2 with the friction shoe removed;

Figure 2 is an end view, partly in vertical cross section, the section being taken substantially on the line 2—2 of Figure 3;

Figure 3 is a side elevational view, partly in vertical section, the section being taken substantially on the line 3—3 of Figure 1;

Figure 4 is a top plan view of one of the identical locking members;

Figure 5 is a side elevational view of the locking member;

Figures 6 to 9 illustrate a modification of the invention, Figure 6 is a top plan view, partly in horizontal section, the section being taken on the line 6—6 of Figure 8 with the friction shoes removed, Figure 7 is an end view, partly in section, the section being taken substantially in the transverse vertical plane as indicated by the line

10 2—2 of Figure 6, Figure 8 is a side elevational view, partly in section, the section being taken substantially in the longitudinal vertical plane as indicated by the line 8—8 of Figure 6; and Figure 9 is a fragmentary sectional view of the top follower comparable to that shown in Figure 8, and illustrating the application of a height adjustment block. In the views certain details may be omitted where more clearly shown in other views.

Describing the invention in detail and referring first to Figures 1 to 5, the spring group comprises top and bottom spring plates 2 and 4 with a set of inner and outer coil springs 6 and 8 positioned 15 at each corner thereof. The top plate comprises a depending peripheral flange 9, confining the upper ends of the springs 6 and 8. The top plate carries a top follower 10 telescoped within an upstanding bottom follower or friction casing 12 formed integral with the bottom plate intermediate the ends thereof and extending transversely of the spring group between the springs at opposite ends of the group. The bottom plate comprises an upstanding peripheral flange 14 surrounding the lower ends of the spring to position the same.

The casing 12 is of rectangular form and comprises interconnected spaced end walls 16, 16 and spaced side walls 18, 18. Each end wall 16 is provided on its internal side with a friction wear plate 20 connected thereto in any convenient manner preferably as by welding at 22, 22.

The top follower 10 comprises spaced side walls 24, 24 and spaced transverse walls 26, 26 interconnecting the side walls intermediate the lateral edges thereof, said side walls and transverse walls 24, 26 extending vertically and being formed integral at their upper ends with the interior or bottom side of the top plate 2. The lower ends of the side walls 24, 24 diverge downwardly at their lateral edges, to provide wedge faces 28, 28 and a pocket 30 adjacent each friction plate 20.

A friction shoe, generally indicated 32, is received within each pocket and is in wedge engagement with the surfaces 28, 28 and the adjacent friction plate 20. Each shoe is actuated by a spring 33 compressed between the shoe and the top plate. The construction of the shoe and the wedge engagement between the shoe and the top follower is substantially the same as that described in Claus J. Werner Clasen, United States Patent No. 2,483,181, for Spring Group, issued September 27, 1949.

It will be appreciated that with the parts as described, the top and bottom sections may sep-

arate and unless means are provided to limit expansion of the spring group, the top follower and the friction shoes may be withdrawn from the bottom follower 12 whereupon the spring group will become dismantled and inasmuch as loads up to about 3,000 pounds per square inch are imposed on the springs 33, it will be appreciated that accidental disassembly could cause severe injury.

The feature of the present invention is the provision of locking means which are retained in the spring group at all times for limiting expansion of the same and maintaining the parts in assembled relationship.

The locking arrangement comprises vertically elongated aligned slots 34, 34 in the side walls 24, 24 of the top follower and registering vertically elongated slots 36, 36 in the side walls 18, 18 of the bottom follower.

The top follower comprises a bottom generally horizontal wall 38 integral with the lower edges of walls 24 and 26 thereof, thereby strengthening said top follower. Centrally on the top side of the bottom wall 38 is formed a T-shaped abutment member, generally indicated 40, said abutment member being disposed between the walls 24 and 26, and comprising a vertical web 42 joined at its lower edge with the bottom wall 38 and at its lateral ends with the walls 26, 26. The upper edge of the web 42 is formed integral with a generally horizontal web 44, spaced above wall 38, and which at its lateral ends is also formed integral with the walls 26, 26. The bottom wall 38 together with webs 42 and 44 forms pockets 46, 46 at opposite sides of the abutment member 40.

Locking keys, generally indicated 48, 48, are received within the top follower at opposite sides of the abutment member 40 through an opening 50 in the top plate 2, the opening 50 being vertically aligned with the hollow space indicated 52 between the walls 24 and 26. Each key or locking device 48 is in the form of a bell crank and comprises a fulcrum or lobe 54 intermediate its ends and a tongue 56 at one end and an upstanding stop member 58 at its other ends, said stop member being formed integral with the rear end of the tongue and extending substantially horizontally at its lower end across the top of the lobe 54. The lobe 54 of each member 48 is received within the adjacent pocket 46, the lobe affording a seat at its lower end as at 60 against the top of the bottom wall of the top follower and affording with the lower extension 62 of the stop member 58 an abutment as at 64 against the underside of the horizontal web 44 of the abutment member 40. The upstanding portion 58 of the locking member is seated at opposite sides of the tongue as at 68 against the interior side of the associated side wall 24 of the top follower. The tongue 56 of each locking member projects through the associated slots 34 and 36. The tongue 56 is adapted for abutment as at 70 with a downwardly facing surface on the associated wall 18 of the bottom follower at the top end of the related slot 36, thereby limiting expansion of the spring group. It will be readily understood that abutment of each locking member 48 at points 60, 64 and 68 prevents rotation of member 48 so that a positive locking action between the top and bottom followers is obtained.

In order to disassemble the spring group, shown in Figures 1 through 5, the package is turned upside down with the top plate seated on a press platen or suitable jig. A load is applied on the

bottom plate compressing the group until the locking members 48, 48 rotate due to gravity at points 64, 64 and the tongues 56, 56 thereof withdraw from the slots 34, 36 whereupon the members 48, 48 will fall into the center opening or space 52 of the top follower. The load may then be released and the spring package will readily disassemble.

To assemble the spring package, the bottom plate is placed on a press platen and the springs 6 and 8 are positioned in the pockets at the corners of the bottom plate. The springs 33 are then inserted into the shoes 32 and the shoes are positioned in the respective pockets 30, 30 in the top follower. The shoes are held assembled with the top plate by bolts (not shown) which may be applied through openings 72 and 74 in the top plate and the shoes. The locking devices 48, 48 are inserted into the opening 52 through the opening 50 and arranged to assume the positions shown in Figure 3. The top plate assembly is then positioned on the springs 6 and 8 whereby the bottom edges 76 of the tongues of the locking members 48 will engage the upper edges 78 of the side walls 18 of the bottom follower. As the load-carrying springs 6 and 8 are compressed, the locking members will rotate upwardly until the tongues are raised high enough to clear the side walls 18, 18 and then on further compression will move between the side walls to points in line with the slots 36, 36 whereupon the tongues 56, 56 will enter the slots 36, 36. Thereupon the pressure on the spring package may be released, the expansion of the package being limited by the locking devices.

Preferably the locking means should lock the spring group when the load springs are at substantially free height. However, under certain circumstances it may be desirable to lock the package with the load springs under substantial initial compression in order to fit the package within a small space. This may be accomplished by applying small non-ferrous, preferably aluminum metal pieces to the upper face 80 of the tongues 56 of the locking members, the metal pieces as shown in phantom lines at 82 in Figure 5 are adapted to engage the upper ends of the slots 36 as at 10. These pieces may, of course, be applied to the upper ends of slots 36. These pieces of non-ferrous metal may be left in after the package has been installed and will disintegrate after a few blows between the tongue and upper end of the slot during oscillation of the spring package.

Figures 6 to 9 illustrate a modification of the invention wherein like parts corresponding to those shown in Figures 1 to 3 are identified by corresponding reference numerals. This modification presents an extension as the idea shown in Figures 1 to 5. The locking arrangement comprises the slots 34 and 36 in the side walls 24 and 18 of the top and bottom followers. In the present modification the locking members, generally indicated 100, 100, are carried by the bottom follower on cradles formed on the outer sides of the side walls. Each cradle comprises a pair of outstanding lugs 102, 102 disposed at opposite sides of the associated slot 36. Each pair of lugs receives the associated locking member 100 therebetween. The locking member is generally L-shaped in side elevation and, as best seen in Figure 8, comprises a depending weight lug 104 which at its upper end merges with one end of a tongue 106. The tongue extends through the slots 36 and 34, and in locking position is an

abutment at its upper edge as at 108 with the upper edge of the associated slot 36 and at its bottom edge adjacent its inner end is an abutment as at 110 with the top side on the bottom wall 38 of the top follower. The locking member is provided intermediate its ends at the juncture of the weight lug 104 and the tongue 106, with fulcrums or trunnions 112, 112, extending from opposite sides thereof and pivoted within complementary recesses 114, 114 in the upper edges of the cradle lugs 102, 102.

In Figure 9 is shown the application of a block 116 of non-ferrous material such as aluminum to decrease the initial height of a spring package as shown, the block 116 is fastened to the upper leg 118 of an U-shaped steel spring clip, the upper leg 118 engaging the top surface of the bottom wall 38 of the top follower, and the lower leg 120 which is joined by a base section 122 to the upper leg 118 engages the bottom side of wall 38. It will be noted that the block 116 is positioned at the bottom of the associated slot 34 and that after a few oscillations of the spring group it will be disintegrated by being pounded between the tongue 108 and the bottom wall 38. It will be noted that the locking members 100, 100 will normally be retained in locking position inasmuch as the weight lugs 104 thereof will tend to rotate the locking members to locking position as best seen in Figure 8. The locking members will not disassemble from the bottom follower in service inasmuch as the axis of pivot of each member is in close proximity to the contact at 108.

In order to disassemble the spring package, the spring package is inverted and seated on its top plate 2 and the package is then compressed whereupon the locking members are pivoted at contacts 108 and will fall out of the cradles and coincidentally withdraw the tongues thereof from the slots 34 and 36, whereupon the spring group may be disassembled by merely separating the spring plates.

In order to reassemble the spring group, the top plate assembly is reassembled as hereinbefore described. The bottom plate is placed in its normal position. The locking members 100, 100 are cradled in the lugs 102, 102 with the tongues extending through the slots 36, 36 into the friction casing or bottom follower. The load-carrying springs are then positioned at the corners of the bottom plate. Then the top plate assembly is mounted on the load-carrying springs and coincidentally the top follower is inserted into the bottom follower. The bottom end or wall 38 of the top follower, after it is entered into the bottom follower, engages the top edges of the tongues of the locking members 100, 100. The spring group is compressed whereupon the keys or locking members are rotated in directions moving the tongues downwardly. The compression is continued until the bottom wall of the top follower clears the lower edges of the tongues, whereupon the locking members will immediately rotate to positions entering the tongues 106, 106 into the slots 34, 34 by the counterweight lugs 104, 104. The pressure on the spring group is then relieved whereupon the spring group will expand as readily seen in Figures 7 and 8.

I claim:

1. A spring group comprising top and bottom plates and load-carrying springs confined therebetween, friction means in parallel with the springs and comprising telescoping top and bottom followers connected to respective plates, each follower having generally vertical spaced side

walls, the side walls on one follower being arranged adjacent the respective side walls of the other follower, and means for limiting expansion of said spring group comprising horizontally aligned, vertically elongated slots in adjacent walls of respective followers, and locking members carried by said one follower adjacent the side walls thereof, each locking member having a tongue adapted to enter the adjacent slots upon predetermined compression of said group through rotation of the locking member, each locking member having abutment with the one follower at vertically separated points spaced longitudinally of the locking member and engageable with the other follower at one end of the related slot.

2. A spring group comprising top and bottom plates, load-carrying springs therebetween, telescoping top and bottom followers connected to respective plates, each follower having generally parallel side walls, the side walls of one follower being arranged adjacent the respective side walls of the other follower, and means for limiting expansion of said spring group comprising horizontally aligned vertically elongated slots in adjacent walls of respective followers, and locking means carried by the top follower between the walls thereof and comprising a locking member adjacent each side wall, each locking member having abutment at one point with a downwardly facing surface of the top follower and having abutment at another point with the interior of the associated side wall of the top follower at an area above said first-mentioned point, each member extending through the slots in adjacent side walls of respective followers and having abutment at its top side with the upper end of the slot in the related side wall of the bottom follower to limit expansion of the spring group.

3. A spring group comprising a bottom follower, a top follower telescoping thereinto, spring means operatively associated with said followers for urging them apart, friction shoes at opposite sides of the top follower in wedge engagement therewith and in frictional engagement with opposed upright surfaces within said bottom follower, springs compressed between the shoes and top follower for actuating the former into said engagement, each follower comprising spaced generally parallel substantially vertical side walls with vertically elongated aligned slots therein, a bottom web interconnecting the lower ends of the side walls of the top follower, retainer keys at opposite sides of said followers between said shoes and carried by one of said followers, said keys extending horizontally through slots in adjacent walls of said top and bottom followers and engaging the top side of said bottom web.

4. A spring group comprising inner and outer vertically movable followers, spring means relating between the followers, said outer follower comprising spaced end walls and spaced side webs, said inner follower comprising spaced side walls, friction shoes extending between said side walls adjacent each end wall and in wedge engagement with the lateral edges thereof and in frictional engagement with respective end walls, resilient means acting between the shoes and top follower urging the shoes into said engagement, and means for limiting expansion of said group comprising a generally horizontal wall on said inner follower, abutment means connected thereto, and keys fulcrumed intermediate their ends against said abutment means and each having one of its ends extending upwardly and in abutment with the internal sides of the related side wall, each key

extending at its other end through an opening of the adjacent side wall into a vertically elongated slot in the adjacent side web.

5. In a spring group, top and bottom telescoping followers, spring means associated therewith and urging them apart, and means for limiting separatory movement of said followers comprising retainer keys at opposite sides of the followers and having horizontal tongues extending through vertically elongated slots in said followers, said keys being rotatably mounted on one of the followers, cooperating means on said keys and one follower for limiting rotation of the keys in a direction moving said tongues from the horizontal to a position permitting separation of said followers, said keys capable of being rotated in the opposite direction against the force of gravity to positions disposing said tongues out of said slots to permit assembly and disassembly of said followers.

6. A spring group, according to claim 5, wherein in the bottom follower comprises spaced lugs at each side thereof at opposite sides of the adjacent slot therein, arcuate seats on the top sides of the lugs, and wherein each key comprises trunnions at one end of its tongue and a downwardly extending weight lug, the trunnions being received on the seats of the adjacent lugs.

7. A spring group, according to claim 5, wherein in the top follower comprises a bottom wall and abutment means thereon and each key is provided with a lobe at one end of its tongue extending between said wall and said abutment means in engagement therewith, and each key having a portion extending upwardly into the top follower along a substantially vertical portion thereof and in engagement therewith.

8. In a spring group assembly, top and bottom plates, top and bottom telescoping followers connected to respective plates, and means for limiting expansion of said group comprising substantially parallel walls on respective followers arranged in adjacent relationship with vertically elongated horizontally aligned slots therethrough, and a locking member carried by one of said followers and having a tongue disposed edgewise vertically and extending through said slots, said tongue being adapted to engage the other follower at one end of the slot in the wall thereof to limit expansion of said group, said locking member being rotatable out of said slots when said group is compressed to accommodate assembly and disassembly thereof.

9. An assembly, according to claim 8, wherein said bottom follower comprises a pair of outwardly extending lugs disposed at opposite sides of the slot therein and said tongue is pivoted at one end on said lugs, a weight lug extending downwardly from said one end of said tongue, an abutment surface at the upper end of the slot in the wall of said bottom follower bearing against the top edge of the tongue, and a surface at the bottom of the slot in the wall of the top follower bearing against the bottom edge of the tongue.

10. A spring group comprising top and bottom plates, spring means confined therebetween, top and bottom telescoping followers carried by respective plates, and means for limiting expansion of the group comprising a locking member buttressed at two points on its top and bottom against one of said followers and extending at one end into a vertically elongated slot in the other of said followers for abutment with said other follower at one end of the slot therein.

11. A spring group, according to claim 10,

wherein said bottom follower telescopes over said top follower and wherein said bottom follower comprises a cradle on its external side pivotally mounting said locking member and wherein said locking member abuts the cradle on its bottom side and at its top side abuts a downwardly facing surface on the bottom follower at a point spaced inwardly of the cradle toward the axis of said followers and wherein said one end of said member extends inwardly of said point and abuts on its bottom side against an upwardly facing surface on the top follower to limit expansion of the group.

12. A spring group, according to claim 10, wherein said member is pivoted to said bottom follower and is rotatable to a position out of engagement with said top follower to accommodate assembly and disassembly of said group.

13. A spring group, according to claim 10, wherein said locking member is located within the lower end of said top follower.

14. A spring group comprising top and bottom telescoping followers, and means for limiting expansion of the group comprising a locking member buttressed at two points on its top and bottom sides against one follower and extending into a vertically elongated slot in the other of said followers for abutment with said other follower at one end of the slot therein, and a disintegrable adjustment block connected to said other follower at said one end of said slot for abutment with said locking member.

15. A spring group comprising top and bottom telescoping followers, means for limiting expansion of the group comprising a key carried by one follower, a wall on the other follower abuttable with said key, a height adjusting block interposed between abutting faces of the key and wall, and means for securing said block to the wall comprising a clip integral with the block and clamped to the wall.

16. A spring group comprising spaced spring plates, spring means for urging said plates apart, a key carried by one plate, a wall carried by the other plate and abuttable with said key to limit separatory movement of said plates, and a disintegrable height adjusting block interposed between said key and said wall.

17. In a spring group, spaced plates, spring means urging said plates apart, and means for limiting separatory movement of the plates comprising a key pivotally fulcrumed to one plate and engaged with the other plate, and means on said one plate for limiting pivotal movement of the key in a direction accommodating separatory movement of the plates.

18. A spring group, according to claim 17, wherein the last mentioned means are characterized by a substantially vertical surface of said one plate engaged with said key.

19. A spring group, according to claim 17, wherein the last mentioned means are characterized by a substantially horizontal surface of said one plate engaged with said key.
